(57) **CLAIM**

The ornamental design for an escutcheon, as shown and described.

DESCRIPTION

FIG. 1 is a top, front, right side perspective view of an esutcheon showing our new design;

FIG. 2 is a bottom, front, left side perspective view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawing figures illustrate portions of the article that form no part of the claimed design.
